SHOE SEWING MACHINE

Bernard T. Leveque, Wenham, Mass., assignor to
 United Shoe Machinery Corporation, Borough
 of Flemington, N. J., a corporation of New
 Jersey

Application August 17, 1940, Serial No. 353,683

10 Claims. (Cl. 112—226)

The present invention relates primarily to shoe sewing machines, and is herein disclosed as embodied in a curved hook needle lockstitch shoe sewing machine adapted to sew the outsole to the welt and upper of a welted shoe, the illustrated embodiment of the invention being similar in certain respects to the machine disclosed in the present inventor's prior Patent No. 2,144,766 of January 24, 1939, and in therein referred-to patents issued on divisional applications based on said patent.

The present invention has as an object the provision in an outsole shoe sewing machine of new and improved mechanisms capable of actuating the various parts in the desired manner at high speed, and which will nevertheless permit the parts to be brought to rest, on stopping the machine, quickly and in proper position without damaging shock or jar.

Another object of the invention is to provide, for use in machines of the above type, improved mechanisms for controlling the machine whereby the operator may, by means of a single control member, start and stop the machine and likewise control the speed of operation thereof.

With these objects in view, a feature of the present invention contemplates the provision in an outsole shoe sewing machine having a main sewing shaft in the form of a multi-throw crank-shaft, means for disconnecting the sewing shaft from its driver, a plurality of separate mechanisms for actuating the stitch forming and work handling devices from the sewing shaft, each of these mechanisms being actuated from a crank of the multi-throw crankshaft, and means for disconnecting the actuated devices from the sewing shaft while permitting continued rotation of the shaft comprising a control member for moving the individual elements of the connections between the sewing shaft and the actuated devices, and means for actuating the control member. Each of these trains of mechanism includes a lever provided with a cam slot within which is received a follower, one of said elements being reciprocated relative to the other by a crank of the sewing shaft to impart to the actuated member a characteristic movement determined by the particular configuration of the cam slot, such arrangement making possible easily driven, smooth running mechanisms capable of high speed operation while permitting stopping of the machine without injurious shock or jar.

In accordance with another feature of the invention, these trains of mechanisms include elements adapted to be disconnected to discon-

nect the various actuated devices from their actuating members so that, upon stopping the machine, the various stitch forming and work handling devices may be brought to rest independently of the crank shaft, the connection and disconnection of these elements being effected by means under the control of the operator, said means likewise being arranged to control a two-speed driving mechanism by which the machine may be operated at high or at low speed, as desired.

An outsole shoe sewing machine embodying the several features of the invention is illustrated in the accompanying drawings, in which Fig. 1 is a view in right-hand side elevation, partly in section, of the head of the machine, showing a portion of the two-speed driving mechanism and certain of the actuating mechanisms for the stitch forming and work handling devices, illustrating particularly the train of mechanism for actuating the take-up, the parts being shown after the disconnection of the disconnectible elements of said train and before the crankshaft has come to rest; Fig. 2 is a detail view in right side elevation of the train of mechanism for actuating the needle, likewise illustrating the parts at the instant of disconnection of the disconnectible link; Fig. 3 is a detail sectional view, on an enlarged scale, taken on the line 3—3 of Fig. 2, showing the arrangement of cam lever and cam roll or follower in the cam slot of said lever; Fig. 4 is a front view, partly in section, showing the crank shaft and the lower ends of the connecting rods or links of the individual actuating mechanisms for the various stitch forming and work feeding devices; Figs. 5 to 10, inclusive, are views taken on the section lines 5—5, 6—6, 7—7, 8—8, 9—9, and 10—10, respectively, of Fig. 4, showing the various angular positions of the different crank throws in order to operate the various devices in proper timed relation, the crankshaft being substantially in its position at the instant of disconnection of the disconnectible elements of the several trains of mechanisms, as in Figs. 1 and 2, Fig. 5 showing the crank for the take-up, Fig. 6 the crank for the work feed, Fig. 7 the crank for the needle, thread hook, and presser foot lock, Fig. 8 the crank for the awl, Fig. 9 the crank for the shuttle and Fig. 10 the crank for the looper; Fig. 11 is a view in rear elevation of a portion of the head of the machine showing certain of the actuating connections of the starting and stopping and speed controlling mechanisms; Fig. 12 is a detail view in left-hand side

elevation, partly in section, and taken on the line 12-12 of Fig. 11, illustrating on a somewhat larger scale the two-speed driving mechanism shown in Fig. 1; Fig. 13 is a detail sectional view of the double-coned clutch member of the driving mechanism, taken on the line 13-13 of Fig. 12; Fig. 14 is a detail view in right side elevation, partly in section, of the take-up mechanism of the machine, showing the thread measuring mechanism and the thread clamp, the take-up arms being shown in extended position for setting the stitch; Fig. 15 is a view in front elevation, partly in section, of the parts shown in Fig. 14, and taken on the line 15-15 of that figure; and Fig. 16 is a view taken similar to Fig. 14, but with the take-up arms together, showing the manner in which the thread measuring mechanism cooperates with the take-up mechanism in pulling off thread from the supply.

The stitch forming and work handling devices adjacent the sewing point comprise, in the machine of the present invention, the work support 20, the presser foot 22, curved hook needle 24, curved awl 26, looper 28, thread arm 30, loop spreader 32 and rotary shuttle 34. These parts are substantially similar in arrangement and mode of operation to those of the machine disclosed in the present inventor's prior Patent No. 2,141,766 above referred to and in the patents issued on divisional applications based thereon.

In order for the various sewing and work handling devices to withstand the repeated shocks and strains of the stitching operation when the machine is operated at high speed, the parts must be strongly constructed, with the result that they are of necessity relatively large and heavy. To actuate these parts in proper timed relation, imparting to each device the desired characteristic movement, in certain cases involving a rapid acceleration and deceleration in but a fraction of a stitch forming cycle, necessarily requires actuating mechanisms that are in themselves strong and durable. As a consequence, the proper actuation of the parts at high speed, and the stopping of the machine quickly without undue shock or jar with the stitch forming and work handling devices in proper position to permit removal of the work, represent serious problems.

In the machine of applicant's prior patent above referred to, the desired results are sought to be accomplished by actuating the principal thread manipulating and work feeding devices from the cam shaft through separate trains of mechanism, and by providing in these trains of mechanism, elements adapted to be disconnected, whereby the principal operating devices of the machine can be brought to rest at a predetermined time in the cycle of operations without simultaneously stopping the rotation of the cam shaft and some of the light and uniformly moving parts actuated thereby. In accordance with the present invention, separate trains of mechanisms are likewise provided for actuating the several stitch forming and work feeding devices, but these mechanisms, instead of comprising cam disks on the main shaft of the machine as in applicant's prior patent, are constructed and arranged for crank actuation while imparting the required movements to the stitch forming and work feeding devices and likewise permitting disconnection of these elements upon stopping the machine.

The well recognized advantages of crank operated mechanisms are thus secured and a ma-

chine is produced having all the novel and desirable characteristics of applicant's patented machine but free from the objectionable features incident to the use of cam operated mechanisms.

The main shaft of the illustrated machine, as best shown in Fig. 4, consists of a crank shaft 36 provided with a plurality of "throws" or cranks, each of which, by suitable connections, actuates a separate train of mechanism for driving the stitch forming or work handling device connected thereto. The individual cranks of the crank shaft 36 are connected to their various stitch forming and work handling devices through mechanisms which convert the simple crank motions into complex movements best adapted for actuating each device according the characteristic motion desired. This is accomplished in the present invention by the provision of members having cam slots within which are oscillated cam followers by connections to the respective cranks of the crank shaft, the configuration of the different cam slots being arranged in accordance with the requirements of the respective actuated devices.

The crank for actuating the needle is indicated at 38 (Figs. 2, 4 and 7) and is connected by means of a link 40 to a rock arm 42 pivotally supported on a cross shaft 44 at the rear of the machine. The forward end of the rock arm is provided with a roll or follower 46, see Fig. 3, which is received within a cam slot 48 in the needle cam lever 50. For each revolution of the crank shaft, the follower is oscillated in an arc from one end of the cam slot to the other and back to the starting point. Therefore, when the actuated device, as in the case of the needle, is to be rapidly moved into a position and immediately retracted, the cam slot adjacent one end is provided with an inclined or non-arcuate portion as at 52, while a dwell for the remainder of the cycle is provided by arcuate portion 54 concentric with the shaft 44 on which the rock arm 42 is pivoted. Since the reversal of movement of the actuated device takes place while the crank is passing through the limit of its throw, at which time the velocity of the follower in the cam slot drops to zero, a smooth running mechanism is obtained which makes possible the use of relatively light-weight parts.

The take-up mechanism, hereinafter described, is actuated from the crank 60 (Figs. 1, 4 and 5) at the left-hand end of the crank shaft 36, as viewed from the front. The crank is connected by link 62 to rock arm 64 pivotally mounted on cross shaft 44, the rock arm being provided at its outer end with a follower roll similar to the one illustrated in Fig. 3 and which is oscillated in an arcuate path along a cam slot in cam lever 68. The "dwell" portion of the cam slot is indicated at 70, while the actuation of the take-up occurs during the traverse by the roll of the inclined portion 72, a brief dwell being provided at the upper end by the short arcuate portion 74, in addition to that afforded by the passage of the crank throw 60 over dead center.

The timing of the take-up relative to the needle is determined principally by the angular position of the take-up crank throw 60 compared with that of the needle crank 38 (see Figs. 5 and 7). Since the crank shaft 36 is preferably of one-piece construction, the positions of the cranks may be accurately located and the proper timing of the parts maintained with no risk of slipping or misadjustment. Variations in the characteristic movements of the devices and

minor adjustments in timing may be quickly and easily effected, however, through substitution of the individual cam levers, and at considerably reduced expense as compared with cam disks.

The crank for actuating the feed mechanism is indicated at 76, with its connecting link at 78, Figs. 4 and 6, while the crank for the awl is shown at 80 in Figs. 4 and 8, with connecting link 82 to the awl rock arm. The shuttle is driven from still another crank 84, Figs. 4 and 9, and the looper from crank 86, Figs. 4 and 10. Each crank actuates through a connecting link and rock arm a cam lever having a cam slot of the configuration to operate the respective device in the required manner, the rock arms being arranged along the cross shaft 44 and the cam levers along a parallel supporting shaft 90.

The various stitch forming and work handling devices are actuated from their respective cam levers through appropriate linkages. In order that the machine may be stopped quickly and without undue shock or jar, the linkages include elements arranged to be disconnected so that the devices may be stopped independently of the crank shaft, rock arms, and cam levers. As a result, only the lighter portions of the mechanisms need be stopped quickly and accurately, the relatively heavier parts being allowed to coast to rest to an indeterminate stopped position. The arrangement and manner of operation of these disconnectible elements are similar in certain respects to those described in the inventor's prior Patent No. 2,098,251 of November 9, 1937. In the present machine, the disconnectible elements are arranged to be connected and disconnected from the cam levers, being moved into and out of operative connection by means of stop mechanism hereinafter described.

The mechanism for actuating the needle from the needle cam lever 50 is illustrated in Fig. 2 and comprises a link 92 pivotally connected at its forward end to one arm of a bell crank 94, the other arm of which is provided with a toothed sector 96 meshing with gear teeth on the needle segment 98. Adjacent its other end, the under side of the link is formed with a notch or recess 100 adapted to fit over a boss 102 of complementary shape carried by the upper end of the cam lever 50. During the operation of the machine, the link is in engagement with the cam lever, being held down by a tension spring 104.

The other stitch forming and work handling devices are likewise actuated from their cam levers by mechanisms which include links disconnectible connected to the cam levers. The disconnectible link for the take-up mechanism is shown at 106 in Fig. 1. The link is connected to one arm of a bell crank 108, the other arm of which has a toothed segment 110 intermeshing with gear 112 on one arm 114 of the take-up, the other arm 116 being driven through gear 118.

The presser foot 22 is actuated to clamp and unclamp the work by means of Horton clutch mechanism similar to that fully illustrated and described in the inventor's U. S. Letters Patent No. 2,098,298 of November 9, 1937. As in said patent, the clutch is arranged to clamp the work upon rocking the inner member in counterclockwise direction. In the present machine, this rocking movement is effected by a lever 120 secured to the shaft 122 upon which the inner or actuating member of the clutch is mounted. The outer or actuated member 124 is connected by link 126 to the bell crank lever 128 to which the presser foot is secured. The lever 120 is pro-

vided with a cam slot 130 within which is reciprocated a roll or follower 132 carried by an upward extension 134 of the needle cam lever 50. The parts are shown in Fig. 1 with the clutch in clamping position, the follower 132 being at the inner end of the cam slot 130, while the clutch is released when the follower is at the outer end of the slot, as indicated by the dotted outline 136.

The crank shaft is journaled in bearings 138 in the machine frame, and is driven through intermeshing spiral gears 140 and 142 from a drive shaft 144 extending through the machine from front to back, the drive shaft being rotated from a motor 146 (see Fig. 12) located in the base of the machine.

In sewing around the more difficult portions of a shoe, it is frequently desirable to sew at a speed considerably less than the speed at which the machine of the present invention is capable of running. Furthermore, although the disconnectible links, actuated as hereinafter described, are fully capable of functioning effectively to disconnect the devices from their cam levers upon throwing the stop mechanism into operation, even though the machine is still rotating at very high speed, nevertheless precise adjustment is required to insure that the stop mechanism will operate at the correct instant in the stitch forming cycle so that excessive strains may be avoided. In view of the fact that the connection and disconnection of the links is effected, as hereinafter described, by means of a single control member or "controller," there is provided in the machine of the present invention a combined stop mechanism and two-speed drive so arranged that the connection and disconnection of the various devices with their actuating cam levers upon starting and stopping the machine takes place while the machine is operating at relatively low speeds, the starting and stopping of the machine and the selection of either high or low speed operation being under the control of the operator through a single foot treadle.

The driving of the machine at either high or low speed is effected by means of two sets of chains and sprockets of different ratios between the motor 146 and the drive shaft 144, the high speed drive comprising motor sprocket 150, chain 152 and drive shaft sprocket 154, while the low speed drive consists of motor sprocket 156, chain 158 and drive shaft sprocket 160. The high speed and low speed sprockets 154 and 160 are mounted by means of ball bearings 162 on the main drive shaft 144 in independently rotatable relation to one another and the shaft, a sleeve 164 and clamping nut 166 serving to maintain the sprockets in proper spaced position on the shaft. Mounted between the sprockets 154 and 160 is a clutch member 168 by which either the high speed or the low speed sprocket may be connected to the drive shaft 144, or both disconnected therefrom upon stopping the machine. The clutch member is provided with external oppositely directed cone surfaces 170, while the sprockets 154 and 160 have internal cone surfaces 172 and 174, respectively. The clutch member is keyed to the drive shaft by keys 176 extending through slots 178 in sleeve 164 and shaft 144, the keys having flanges 180 for attachment to the hub of the member 168.

To move the clutch member into and out of engagement with one or the other driving sprockets, the inner ends of the keys 176 are received

in seats formed in a stub shaft 182 axially slideable in a bore 184 in the end of the drive shaft 144. The projecting end of the stub shaft is formed with a ball 186 received within a socket in the upper end of a rod 188 telescoping within an arm 190 which is secured to one end of a rock shaft 192 pivotally mounted in lugs 194 at the rear of the machine frame.

The rock shaft 192 is actuated to shift the stub shaft 182 and clutch member 168 axially of the main shaft 144 through connections controlled from a foot treadle 196 at the base of the machine. These treadle controlled connections include toggle mechanism so arranged that when the treadle is in raised or released position, the clutch member is midway between the sprockets and thus out of engagement with either. On partially depressing the treadle, the clutch member is moved into engagement with the low speed driving sprocket 160, while fully depressing the treadle shifts the clutch member into engagement with the high speed driving sprocket 154.

The toggle mechanism, best illustrated in Figs. 11 and 12, comprises a yoke arm 198 secured to rock shaft 192, a cross pin 200 pivotally received in the outer ends of the yoke, and toggle arms 202 and 204. The arm 202 is pivoted on a shaft 206 secured by set screw 208 in a bracket 210 clamped to the machine frame, while the other toggle arm 204 is in the form of a rod slidable diametrically through pin 200 in the yoke arm 198. The outer end of the arm 204 is provided with a stop washer 212 and check nuts 214, while a compression spring 216 surrounds the rod between pin 200 and the shoulder of an eye portion 218 received between the forked end 220 of arm 202, a pin 222 extending through the parts 218 and 220 to connect the two arms of the toggle.

To raise or lower the toggle and thereby shift the clutch member, the arm 202 is provided at one side with a lug 224 (see Fig. 11) through which a rod 226 extends from the foot treadle 196. Collars 228 fixed to the treadle rod 226 above and below the lug 224 position the toggle arms in the position shown in Fig. 12 when the treadle is held, by spring 230 in raised position against stop screw 232. As shown in said figure, the toggle junction is slightly above its center line, indicated by dot-and-dash line 234, and the clutch member is midway between the drive sprockets and thus in disconnected position. When the treadle is depressed far enough to draw the toggle into straightened position, represented by line 234, the arm 190 is rocked to the right (dot-and-dash line 236) to cause the clutch member to engage slow speed sprocket 160. When the treadle is fully depressed, the toggle arms are drawn into the position shown by dot-and-dash line 238, rocking arm 190 to the left (dot-and-dash line 239) and urging the clutch member to the left into engagement with the sprocket 154 to drive the machine at high speed. On releasing the treadle, the above operations take place in the reverse manner, the engagement of the slow speed drive prior to final disengagement of the clutch serving to slow the machine down substantially before the disconnection of the links and the final stopping of the sewing and work handling devices.

The mechanism for disconnecting the disconnectible links from their actuating cam levers upon stopping the machine while the crankshaft is rotating, though at reduced speed, as a result

of the disengagement of the high speed drive and brief connection of the low speed drive prior to final disengagement, comprises a control member or "controller" in the form of a rock shaft 240 (see Figs. 1 and 2) provided with a series of arms 242, each arm having at its forward end a socket or recess 244 arranged to receive a downwardly projecting boss 246 of semi-cylindrical shape formed at the rear end of each disconnectible link. The rock shaft 240 is arranged to be actuated to cause the arms 242 to engage their respective links at a time in the operation of the machine when the cam levers, due to the particular configurations of the individual cam slots, are experiencing dwells. Upon disconnection of the links from the cam levers, the links and their actuated devices are locked in stopped position by engagement of the bosses 246 with sockets 244 in the arms 242.

The actuation of rock shaft 240 to disconnect the links upon stopping the machine and to reconnect the same upon starting is effected by starting and stopping cams 248 and 250 mounted on each side of a gear 252 (see Figs. 1, 2 and 11) driven by gear 254 from the crankshaft 36. The cams 248 and 250, together with the gear 252, are mounted upon a sleeve which is splined so as to be capable of sliding longitudinally on the supporting shaft 256. On stopping the machine, the cams are shifted along the supporting shaft 256 to bring the stopping cam 250 into engagement with a follower on a stopping lever 258, while to start the machine, the starting cam 248 is brought into operative relation with a follower on starting lever 260. The cams are shifted, as hereinafter described, by means of an arm 268 engaging a groove 270 in the sleeve on which the cam and the gear 252 are mounted. The levers 258 and 260 are connected to an upwardly extending arm 262 connected by a short link 264 to an arm 266 secured to rock shaft 240. The arm 262 and link 264 form a toggle which is straightened upon stopping the machine to rock the disconnecting arms 242 of the controller upwardly, the toggle being broken upon starting the machine to rock the controller in the opposite direction and thereby lower the disconnectible links into engagement with their cam levers.

In order that the actuation of the rock shaft upon starting and stopping the machine may be accurately synchronized with the operation of the two-speed driving mechanism, the shifting of the starting and stopping cams longitudinally of the shaft 256 is effected by connections from the treadle rod 226 by which the clutch of the two-speed driving mechanism is controlled. These connections comprise an arm 268 having a forked upper end engaging the groove 270 in the starting and stopping cam assembly, a rock shaft 272 on which the arm is mounted, and a second arm 274 secured to the outer end of the rock shaft, said arm being provided with a pivotally mounted block 276 through which the upper end of the treadle rod 226 passes. The rock shaft 272 likewise carries a forked arm 278 provided with adjustable stop screws 280 adapted to engage a fixed lug 282 to limit the longitudinal movement of the starting and stopping cams. A stop collar 284 is secured to the treadle rod below the block 276, while a compression spring 285 between the top of the block and an adjusting nut 287 on the treadle rod provides a yielding connection upon downward movement of the treadle rod.

With the above described arrangement, depression of the treadle to start the machine serves both to connect the drive shaft to the motor through the low speed drive and also to shift the starting cam into position to engage the starting lever 260 so that, at the proper time in the rotation of the crank shaft 36, the rock shaft 240 is turned in counterclockwise direction to lower the disconnectible links into engagement with their actuating levers. Further depression of the treadle operates as hereinbefore described to disconnect the low speed drive and to throw the high speed drive into operation, the spring 285 yielding to permit the treadle rod to slide downwardly relative to arm 274. When the treadle is released to stop the machine, the high speed drive is first disconnected and the slow speed drive connected, and thereafter the collar 284 engages block 276 to shift the stopping cam into operative position and effect disconnection of the links while the clutch member 168 is moved into neutral position to permit the drive shaft and crank shaft to coast to rest.

In order that the stitches may be set with the thread locks a uniform distance below the surface of the work regardless of variations in the thickness thereof, the machine of the present invention is provided with mechanism arranged to cooperate with the take-up, during the passage of the loop of needle thread over the shuttle, to measure in relation to the thickness of the work the amount of thread drawn off from the supply so that the proper length will be available for setting the stitch with the lock at the desired depth. The take-up mechanism, already referred to, is similar to that illustrated in the applicant's Patent No. 2,097,462, dated November 2, 1937, in that the take-up arms 114 and 116, in setting the stitch, are moved from a position in which they are substantially parallel (see Fig. 16), into a position of substantial alignment at the limit of their taking-up stroke, as shown in Figs. 1 and 15, with the result that the amount of thread taken up is unaffected by overthrow of the parts. During the take-up stroke, a thread clamp having fixed and movable gripping jaws 286 and 288, respectively, is caused to clamp the thread between the take-up and the supply, while during the upward movement of the thread loop over the shuttle, the thread clamp is opened to permit thread to be drawn from the supply as required.

The thread measuring mechanism for determining the amount of thread drawn off from the supply relative to the thickness of the work comprises a thread finger 290 adjustably secured by set screw 292 in a bore in one end of a bar 294. The bar extends forwardly through the machine frame with the finger 290 in position to engage the portion of the thread loop between the take-up arms when the latter are in parallel or retracted position, as in Fig. 16. The thread finger is positioned to draw aside more or less thread, and therefore cause to be pulled off from the supply a greater or a lesser amount of thread, by connections controlled by the position of the presser foot when in clamping position. The bar 294 is slidably mounted in the machine frame and is connected at its rear end to one arm of a lever 296 by means of a short link 298. The other arm of lever 296 is connected by a link 300 to a lug 302 on the outer clutch member 124 of the presser foot actuating mechanism. Since the angular position of member 124 when in clamping position is directly dependent on the thickness of the work

engaged by the presser foot, the setting of the thread measuring finger 290 is likewise controlled by the work thickness. For thin work, when the presser foot is relatively close to the work support, the thread finger is in extended position, indicated by dotted line 304 in Fig. 16, and thus has no appreciable effect on the amount of thread drawn off as the thread loop passes over the top of the shuttle. As the thickness of the work increases, the thread finger is moved inwardly so that the thread is engaged before the take-up arms reach fully retracted position, diverting the thread loop and thus causing additional thread to be pulled off from the supply in an amount which will permit the thread lock to be drawn the proper distance into the work when the stitch is set by the take-up.

The thread clamp is actuated to grip the thread during the setting of the stitch by means of a cam 306 on drive shaft 144, the cam having an axial cam slot 308 in which is received a follower 310 on a rock arm 312 pivotally mounted on the machine frame. The arm 312 is provided with a block 314 through which passes a reduced end portion of a bar 316 on which the movable gripping jaw 288 is mounted. A compression spring 318 provides a yielding connection when the arm 312 is rocked in clamping direction, while check nuts 320 retract the bar 316 on the release stroke.

The thread measuring mechanism herein disclosed forms the subject-matter of a divisional application Serial No. 420,548, filed November 26, 1941.

The nature and scope of the present invention having been indicated, and a machine employing the several features of the invention having been specifically described, what is claimed is:

1. An outsole shoe sewing machine having, in combination, stitch forming and work feeding devices, a crank shaft, driving means therefor, separate trains of connections for actuating certain of said devices from the crank shaft, each comprising a member provided with a cam slot, a follower in the slot, a crank and connections for imparting a relative movement to the member and follower lengthwise of the slot, said follower and member being mounted for relative back and forth movement transversely of the slot during the movement of the follower lengthwise of the slot, means for transmitting said back and forth movement to one of said devices comprising an element movable to disconnect said device from the crank shaft, means for disconnecting the crank shaft from its driving means, means comprising a control member for moving said elements, and means for actuating said control member to disconnect the actuated devices from the shaft while permitting continued rotation of the shaft to final stopping position.

2. An outsole shoe sewing machine having, in combination, stitch forming and work feeding devices, a crank shaft, driving means therefor, separate trains of connections for actuating certain of said devices from the crank shaft, each comprising a member provided with a cam slot, a follower in the slot, a crank and connections for reciprocating the follower lengthwise of the slot, said member being mounted for movement back and forth transversely of the slot during the reciprocation of the follower, means for transmitting said back and forth movement to one of said devices comprising a link disconnectibly connected to said member, means for disconnecting the crank shaft from its driving means, means comprising a control member for moving said link

to disconnect it from said slotted member, and means for actuating said control member to disconnect said link while permitting continued rotation of the crank shaft to final stopping position.

3. An outsole shoe sewing machine having, in combination, stitch forming and work feeding devices, a crank shaft, driving means therefor, separate trains of connections for actuating certain of said devices from the crank shaft, each comprising a lever provided with a cam slot extending lengthwise thereof, a follower in the slot, a crank and connections for reciprocating the follower in the slot to produce a back and forth movement of the lever, means for transmitting said movement to one of said devices comprising a link disconnectibly connected to said lever, means for disconnecting the crank shaft from its driving means, means comprising a control member for moving said link to disconnect it from said lever, and means for actuating said control member to disconnect said link while permitting continued rotation of the crank shaft to final stopping position.

4. An outsole shoe sewing machine having, in combination, stitch forming and work feeding devices, a crank shaft, driving means therefor, separate trains of connections for actuating certain of said devices from the crank shaft, each comprising a member provided with a cam slot, a follower in the slot, a crank and connections for imparting a relative movement to the member and follower lengthwise of the slot, said follower and member being mounted for relative back and forth movement transversely of the slot during the movement of the follower lengthwise of the slot, means for transmitting said back and forth movement to one of said devices comprising an element movable to disconnect said device from the crank shaft, means for disconnecting the crank shaft from its driving means, and means for moving said movable elements upon stopping the machine to bring said devices to rest while permitting continued rotation of the crank shaft to final stopping position.

5. An outsole shoe sewing machine having, in combination, stitch forming and work feeding devices, a crank shaft, driving means therefor, a plurality of trains of mechanism for actuating certain of said devices from the crank shaft, each comprising a rock arm, a link connecting said arm with a crank of the crank shaft, a lever provided with a cam slot therein, a follower carried by the rock arm and sliding within the cam slot to rock the lever, and connections between the lever and its actuated device.

6. An outsole shoe sewing machine having, in combination, stitch forming and work feeding devices including a work piercing needle and a presser foot adapted to clamp and unclamp the work, a crank shaft, driving means therefor, mechanisms for actuating the devices from the crank shaft, the mechanism for actuating the presser foot comprising a Horton clutch having actuating and actuated elements, means connecting the presser foot with the actuated element of the clutch, a lever provided with a cam slot therein and connected with the actuating element of the clutch, and a follower engaging the cam slot and actuated by the crank shaft to cause the clutch to clamp and unclamp the work.

7. A machine having, in combination, devices cooperating to perform an operation, a drive shaft, driving means therefor including high speed and low speed driving mechanisms, sepa-

rate trains of mechanisms for actuating the devices from the drive shaft, the trains of mechanisms including elements adapted to be disconnected to disconnect the devices from the shaft, and control means operative on stopping the machine to disconnect the high speed driving mechanism and connect the low speed drive and thereafter to disconnect the disconnectible elements of the trains of mechanisms while disengaging the drive shaft from its driving means to permit rotation of said shaft to final stopping position.

8. A machine having, in combination, devices cooperating to perform an operation, a drive shaft, driving means therefor including high speed and low speed drivers, a plurality of separate trains of mechanisms for actuating the devices from the drive shaft, the trains of mechanisms including elements adapted to be disconnected to disconnect the devices from the shaft, a clutch member shiftable to connect the high speed or the low speed driver to the shaft, and single control means operable to shift the clutch member and to connect and disconnect the disconnectible elements, said means being operative, on stopping the machine, to shift the clutch member out of engagement with the high speed driver and into engagement with the low speed driver and thereafter to disconnect the disconnectible elements of the trains of mechanisms while disengaging the clutch member from the low speed driver to permit rotation of the drive shaft to final stopping position.

9. A machine having, in combination, devices cooperating to perform an operation, a drive shaft, driving means therefor including high speed and low speed driving mechanisms, separate trains of mechanisms for actuating the devices from the drive shaft, the trains of mechanisms including elements movable to connect and disconnect the actuated devices from the shaft, means including starting and stopping cams and starting and stopping cam levers for moving the elements to connect and disconnect the actuated devices from the shaft on starting and stopping the machine, a treadle, and treadle actuated connections operative, on starting the machine, to connect the low speed drive and likewise render operative the starting cam and starting cam lever to connect the movable elements of the trains of mechanisms and thereafter to disconnect the low speed drive and connect the high speed drive, and operative, on stopping the machine, to disconnect the high speed drive and connect the low speed drive, and thereafter render operative the stopping cam and stopping cam lever to disconnect the actuated devices from the shaft while disengaging the shaft from its driving means.

10. A machine having, in combination, devices cooperating to perform an operation, a drive shaft, driving means therefor including high speed and low speed drivers, a plurality of separate trains of mechanisms for actuating the devices from the drive shaft, the trains of mechanisms including elements adapted to be disconnected to disconnect the devices from the shaft, means for connecting and disconnecting the elements comprising starting and stopping cams and starting and stopping cam levers normally out of cooperating relationship, a clutch member normally in disengaged position intermediate the high speed and low speed drivers, and means for controlling the clutch member and the starting

and stopping cams comprising a treadle and a treadle rod, toggle connections actuated by movement of the treadle rod in one direction to shift the clutch member from disengaged position first to one side into engagement with the low speed driver and thereafter to the other side into engagement with the high speed driver, and connec-

5 tions actuated by said treadle rod upon engagement of the clutch member with the low speed driver to shift the starting cam into cooperating relation with the starting cam lever to effect connection of the disconnectible elements of the trains of mechanisms.

BERNARD T. LEVEQUE.
